EP 002514877-0003 5/2014

* cited by examiner

Primary Examiner — Susan E Krakower*Assistant Examiner* — Ramzi Almatrahi(74) *Attorney, Agent, or Firm* — Wolf, Greenfield & Sacks, P.C.(57) **CLAIM**

The ornamental design for a digital camera, as shown and described.

DESCRIPTION

FIG. 1 is a front, top and right side perspective view of a digital camera showing my new design;
 FIG. 2 is a rear, top and left side perspective view thereof;
 FIG. 3 is a front view thereof;
 FIG. 4 is a rear view thereof;
 FIG. 5 is a top plan view thereof;
 FIG. 6 is a bottom plan view thereof;
 FIG. 7 is a right side view thereof; and,
 FIG. 8 is a left side view thereof.

The broken lines depict portions of a digital camera in which the design is embodied that form no part of the claimed design.
